Inventor

A. J. MOORE

By *Watson E. Coleman*

Attorney

UNITED STATES PATENT OFFICE.

ANDREW J. MOORE, OF TUSCALOOSA, ALABAMA.

WRENCH.

1,255,206.

Specification of Letters Patent.

Patented Feb. 5, 1918.

Application filed June 18, 1917. Serial No. 175,451.

To all whom it may concern:

Be it known that I, ANDREW J. MOORE, a citizen of the United States, residing at Tuscaloosa, in the county of Tuscaloosa and State of Alabama, have invented certain new and useful Improvements in Wrenches, of which the following is a specification, reference being had to the accompanying drawings.

10 This invention relates to certain improvements in wrenches and has relation more particularly to a device of this general character particularly designed and adapted for use in connection with pipes or the like and it is an object of the invention to provide a device of this general character having novel and improved means whereby an effective grip may be had upon the work.

It is also an object of the invention to 20 provide a device of this general character including a pivoted jaw and a co-acting sliding jaw together with means for constantly urging the sliding jaw toward the pivoted jaw.

25 The invention consists in the details of construction and in the combination and arrangement of the several parts of my improved wrench wherein certain important advantages are attained and the device rendered simpler, less expensive and otherwise more convenient and advantageous for use, as will be hereinafter more fully set forth.

The novel features of my invention will hereinafter be definitely claimed.

35 In order that my invention may be the better understood I will now proceed to describe the same with reference to the accompanying drawings, wherein:

Figure 1 is a view partly in side elevation and partly in section of a wrench constructed in accordance with my invention;

Fig. 2 is a sectional view taken substantially on the line 2—2 of Fig. 1;

Fig. 3 is a sectional view taken substantially on the line 3—3 of Fig. 1.

As disclosed in the accompanying drawings 1 denotes an elongated shank having one end portion enlarged as at 2 to afford a lateral extension and wherein said lateral extension is provided with a bore 3 disposed longitudinally of the shank 1. The opposite end portion of the shank 1 has an edge thereof provided with the longitudinally disposed ratchet teeth 4.

55 Co-acting with the end portion of the

shank 1 provided with the teeth 4 is the swinging jaw 5 substantially L-shaped in form and having a face of its stem portions 6 provided with a recess 7 into which extends the co-acting end portion of the shank 60 1 and said stem 6 and shank 7 are pivotally connected one to the other through the medium of the pin 8 disposed therethrough and intersecting the recess 7. The inner edge of the foot portion 9 of the jaw 5 is 65 provided with the inwardly facing teeth 10.

Mounted upon the shank 1 inwardly of the jaw 5 is the sliding jaw 11. The jaw 11 is provided with a longitudinally disposed bore or opening 12 through which the shank 1 is disposed and the forward wall of said bore 12 at its inner portion is provided with the teeth 14 adapted to interlock with the ratchet teeth 4 hereinbefore referred to. The wall 15 of the bore 12 opposed to the wall provided by the teeth 14 is inclined inwardly and outwardly as clearly disclosed in Fig. 1 whereby it will be at once perceived that sufficient rocking movement may be imparted to the jaw 11 to 75 disengage the teeth 4 and 14 in order to permit the desired sliding movement of the jaw 11 upon the shank 1. The jaw 11 is provided with the inclined toothed face 16 adapted to co-act with the foot 9 of the jaw 85 5 to effect the requisite engagement upon a pipe or other work.

The outer end portion of the jaw 11 adjacent the inclined wall 15 is provided with a lateral extension 17 provided in its outer 90 end with a recess 18 as indicated by dotted lines and in which extends an end portion of a rod 19, said rod 19 being pivotally held within said recess 18 through the medium of the pin 20. The opposite end portion of the rod 19 is slidably engaged within the bore 3 of the lateral extension 2 hereinbefore referred to and interposed between the inner end of the lateral extension 2 and the outer end of the extension 17 is an 95 expandable member 21 herein disclosed as a conventional coil spring encircling the rod 19. The member 21 serves to constantly urge the jaw toward the rocking jaw 5 so that an effective gripping action of the 100 jaws 5 and 11 upon a pipe or other work is assured. It will also be perceived that during the working operation the expandable member 21 will cause to automatically disengage the teeth 4 and 14 upon a return 110

stroke of the shank 1. The portion of the shank 1 extending within the recess 7 of the swinging jaw 5 is provided with a lateral extension 21 having its periphery concentric to the pin 8. The extension 21 snugly fits within the inner portion of the recess 7 so that a pin 8 is relieved of the strain during the working operation and to impose the pressure directly upon the shank 1 as is believed to be clearly illustrated in Fig. 1.

From the foregoing description, it is thought to be obvious that a wrench constructed in accordance with my invention is particularly well adapted for use by reason of the convenience and facility with which it may be assembled and operated and it will also be obvious that my invention is susceptible of some change and modification without materially departing from the appearance and spirit thereof and for this reason I do not wish to be understood as limiting myself to the precise arrangement and formation of the several parts herein shown in carrying out my invention in practice except as hereinafter claimed.

I claim:

A pipe wrench comprising a shank, a jaw pivotally engaged with an end portion of the shank, a slidable jaw mounted upon the shank and co-acting with the pivoted jaw, opposed walls of the bore of the sliding jaw being in divergence, the inner end portion of one of said opposed walls being provided with teeth, the adjacent face of the shank being provided with teeth adapted to interlock with the first named teeth, a lateral extension carried by the shank at a point remote from the pivoted jaw, said lateral extension being provided with a bore, a rod pivotally engaged with the outer end of the sliding jaw and extending within the bore of the lateral extension of the shank, and a spring encircling the rod and interposed between the outer end of the sliding jaw and the inner end of the lateral extension.

In testimony whereof I hereunto affix my signature in the presence of two witnesses.

ANDREW J. MOORE.
